UNITED STATES PATENT OFFICE.

JOHN H. THOMPSON, OF CHICAGO, ILLINOIS, ASSIGNOR OF ONE-TENTH TO CARTER RADIO COMPANY, OF CHICAGO, ILLINOIS, A CORPORATION OF ILLINOIS.

DESIGN FOR A RADIOLoop OR SIMILAR ARTICLE.

Application filed January 8, 1925. Serial No. 11,971. Term of patent 7 years.

To all whom it may concern:

Be it known that I, JOHN H. THOMPSON, a citizen of the United States, residing at Chicago, in the county of Cook and State of Illinois, have invented a new, original, and ornamental Design for Radioloops or Similar Articles, of which the following is a specification, reference being had to the accompanying drawing, forming a part thereof.

Fig. 1 of the drawing represents a side

elevation and Fig. 2 an end view of a radio loop or antenna, showing my new design.

I claim:

The ornamental design for a radio loop or similar article, as shown.

In testimony whereof I have signed my name in the presence of a subscribing witness.

JOHN H. THOMPSON.

Witness:

C. B. THOMPSON.
